UNITED STATES PATENT OFFICE.

ALBERT JOHN BOND, OF LONDON, ENGLAND.

CARBON-PAPER HOLDER.

960,488.

Specification of Letters Patent. Patented June 7, 1910.

Application filed July 19, 1909. Serial No. 508,459.

To all whom it may concern:

Be it known that I, ALBERT JOHN BOND, of London, England, have invented certain new and useful Improvements in Carbon-Paper Holders; and I do hereby declare the following to be a full, clear, and exact description of the same, reference being had to the accompanying drawings, forming a part of this specification, and to the reference-numerals marked thereon.

The present invention relates to carbon paper holders for use in typewriting and similar machines and it has for an object to provide a simple and inexpensive construction which will permit the holding of one or more carbon sheets in proper positions with relation to the sheets of paper.

Another object of the invention is to provide a construction for facilitating the introduction into the machine of the holder with any suitable number of carbons and sheets of paper.

To these and other ends the invention consists in certain improvements and combinations of parts all as will be hereinafter more fully described, the novel features being pointed out in the claims at the end of the specification.

In the drawings: Figure 1 is an enlarged detail section of one embodiment of the holder in open position; Fig. 2 is a like sectional view showing a sheet of carbon within the holder illustrated in Fig. 1 ready for insertion in the typewriter; Fig. 3 is a similar section showing another position of the holder illustrated in Fig. 1; Fig. 4 is an enlarged detail section of another embodiment of the invention; Fig. 5 is a similar section of the same embodiment showing the manner in which the carbon sheet is first secured; Fig. 6 is a similar section of the same embodiment showing the final position of the parts preparatory to introduction into the machine; Fig. 7 is a detail plan view of the holder shown in Figs. 4 to 6; Fig. 8 is a detail plan view of the same embodiment with a portion of the flap broken away to expose the backing sheet or member below the flap; Fig. 9 is a detail view of said embodiment illustrating the manner in which the flap is interlocked with the backing sheet or member; and Fig. 10 is a detail plan view of the embodiment shown in Figs. 1 to 3.

In the embodiment of the invention illustrated in Figs. 1 to 3 and 10, there is em-

ployed a backing sheet or member 1 which preferably is slightly larger in size than the carbon sheets and is made of any suitable material such as heavy or stiff paper. 60 Hinged along its outer edge to this backing sheet at 2 preferably along a line parallel with the upper edge of the backing sheet, is a flap 3 which extends over said backing sheet and has on the under side a device for 65 securing the carbon sheet 4. In this instance, this device comprises a flap 5 with a hinge 6 parallel with the hinge 2 and in proximity to the free edge of the flap 3 so that the free edge of the flap 5 will, when 70 the latter is moved to lie parallel with the flap 3, lie substantially at the hinge 2.

In order to facilitate the introduction of the carbon holder into the typewriting machine, it may be provided with an introducing member 7 projecting from the backing sheet 1 beyond the carbon securing means formed by flap 3 and flap 5. Preferably this embodiment of the invention is constructed from a single sheet of material 80 which is folded upon itself at 8 and has the portions in proximity to the fold secured together by an adhesive or other means to provide the introducing member 7 with the backing sheet 1 lying on one side thereof 85 and the main flap 3 on the other side thereof, the sheet being then creased at 2 to provide the hinge and having the flap 5 secured to its under surface by a flange 9 or other suitable means. To use this embodiment, one or 90 more carbon sheets 4 are placed upon the backing sheet 1 so that their upper edges lie close to the hinge 6 when the parts are in the positions illustrated in Fig. 3. The flap 5 is then dropped so that its free edge lies 95 substantially at the hinge 2 as shown in Fig. 1, when the flap 3 may be folded onto the backing sheet 1. The free edge of the flap 5 will cause the carbon sheet or sheets to fold in the manner shown in Fig. 2 and thus 100 effectively secure said sheet against movement. Sheets of paper may now be introduced in proper position in the holder and the holder with the carbon sheets and sheets of paper placed within the machine, the portion 105 7 facilitating the introduction as it is of uniform thickness and does not vary with the number of sheets used.

In the embodiment shown in Figs. 4 to 9 no introducing member is employed and 110 the sheet material is creased at 2^a to provide the flap 3^a on one side and the backing

sheet 1^a on the other. On the under side of the flap 3^a is secured the flap 5^a by means of a flange 9^a formed by folding a strip of sheet material at 6^a upon itself in the manner shown in Fig. 5. With this arrangement the free edge of the flap 5^a lies substantially at the fold 2^a of the flap 3^a so that when the latter is bent over the backing sheet 1^a after the carbon sheet 10^a has been introduced in the manner shown in Fig. 5, the carbon sheet will be folded in the manner shown in Fig. 6, thus securely holding said carbon against movement.

In both embodiments of the invention there may be employed some means for securing the flap 3 and 3^a against movement in its folded position. Preferably this means is located at the two ends of the flap and comprises tongues 11 extending toward each other and formed by outwardly converging slits 12 in the backing sheet to receive beneath them tongues 13 extending away from each other and formed by outwardly diverging slits 14 in the end sides of the flap 3 or 3^a. This arrangement permits the interlocking of the flap 3 or 3^a with the backing sheet with a great deal of ease and at the same time does not add materially to the cost of manufacturing the article.

A carbon sheet holder constructed in accordance with this invention is very simple to manipulate; the cost of manufacture thereof is not great, and if made of strong paper, it will last a very long time.

I claim as my invention:

1. A carbon sheet holder comprising a backing sheet, a flap extending over the same and having its outer edge hinged to the sheet, and a carbon paper securing device on the under side of the flap having a

free edge located substantially at the hinge of the flap to cause the carbon paper to fold at this point.

2. A carbon sheet holder comprising a backing sheet, a flap extending over the same and hinged along its outer edge to the sheet, and a hinged flap carried by the under side of the first named flap and having its free edge located substantially at the hinge of said first named flap. 50

3. A carbon sheet holder comprising a backing sheet, a flap extending over the sheet and hinged along its outer edge to the sheet, and a second flap hinged to the under side of the first named flap away from the free edge of the latter and having its free edge located substantially at the hinge of the first named flap. 55

4. A carbon sheet holder comprising a backing sheet, a hinged flap extending over the backing sheet, a carbon securing flap carried by the under surface of the first-named flap and having its free edge located substantially at the hinge of the first-named flap, and an introducing member lying on the outer side of the hinge of the flap. 60

5. A carbon sheet holder comprising a single sheet of material folded upon itself, the portions in proximity to the fold being secured together to provide an introducing member and the portion on one side of the fold beyond the secured portion acting as a backing sheet while that on the other side of the fold beyond the secured portion acts as a hinged flap overlying the backing sheet. 70

ALBERT JOHN BOND.
